UNITED STATES PATENT OFFICE.

PETER DE MATTIA AND BARTHOLD DE MATTIA, OF CLIFTON, NEW JERSEY.

DESIGN FOR AN AUTOMOBILE-TIRE.

• 50,269.

Specification for Design.

Patented Feb. 6, 1917.

Application filed October 28, 1916. Serial No. 128,329. Term of patent 14 years.

To all whom it may concern:

Be it known that we, PETER DE MATTIA and BARTHOLD DE MATTIA, both citizens of the United States, and residents of Clifton, in the county of Passaic and State of New Jersey, have invented a new, original, and ornamental Design for an Automobile-Tire.

Reference is to be had to the accompanying drawings in which—

The figure is a face view of a fragment of an automobile tire showing the tread portion thereof.

We claim—

The ornamental design for an automobile tire as shown.

PETER DE MATTIA.
BARTHOLD DE MATTIA.
